UNITED STATES PATENT OFFICE.

TOWNSEND DE M. HAWKES, OF CORNING, NEW YORK, ASSIGNOR TO T. G. HAWKES & CO., OF CORNING, NEW YORK, A CORPORATION OF NEW YORK.

FRENCH-DRESSING BOTTLE.

1,188,172.

Specification of Letters Patent. Patented June 20, 1916.

Application filed December 14, 1914. Serial No. 877,200.

To all whom it may concern:

Be it known that I, TOWNSEND DE M. HAWKES, a citizen of the United States, residing at Corning, in the county of Steuben 5 and State of New York, have invented a certain new and useful French-Dressing Bottle, of which the following is a specification.

This invention relates to a bottle for measuring, confining and emulsifying the oily 10 and aqueous ingredients of the well-known condiment, French dressing. It has long been customary to mix oil and vinegar in preparing French dressing, by beating these ingredients together with desired seasoning 15 in an open receptacle in proportions more or less accurately determined through means of a spoon or other conveniently available measure, but this method of producing the dressing does not thoroughly mix the ingredients, except at considerable inconvenience; 20 it is inaccurate; and it leaves the dressing exposed and without facility for economically dispensing it.

The object of the present invention is to 25 provide a combined proportioning, emulsifying, storing and dispensing receptacle for French dressing, and it consists in a bottle preferably elongated and adapted to stand erect, constructed for convenient introduction of the dressing ingredients, having thereon measuring markers located to indicate, when the bottle stands erect, the surface level of the appropriate quantity of one constituent and also the surface level of the 30 aggregate quantity of both constituents; having a free space above the aggregate quantity marker which, added to the measuring spaces, provides a relatively long and narrow agitating chamber; said bottle also 35 having beyond said free space, a discharge opening, a closure therefor, and a reduced and shouldered handhold around the discharge opening; the bottom being shaped to provide a broad impact and spreading 40 surface against which the contents impinges when being shaken; the shoulders of the reduced handhold at the neck forming inclined surfaces which deflect the fluid inward as it impinges thereagainst, thus increasing the 45 sub-dividing and mixing effect; and the closure being preferably provided with a finger bearing for conveniently receiving the finger, to resist displacement of the stopper when the bottle is retained by the hand- 50 hold and shaken to agitate the contents.

The invention will be fully understood upon reference to the accompanying drawing and the following detailed description of the illustrative embodiment shown thereon.

In said drawing, Figures 1 and 3 are front elevations of the bottle, disclosing different markings therefor, and Fig. 2 is a section on the line 2^x—2^x of Fig. 1 or Fig. 3.

1 represents the body of the bottle, which is greater in height than in width, although not limited to any particular design or shape. This bottle is adapted to contain the ingredients to be mixed, and in order that it may also serve as an accurate measure of these ingredients, it is provided with a lower marker 2, preferably in the form of a score or cut in the surface, located so that when the bottle stands upright, it will indicate the surface level of the appropriate quantity of one of the ingredients to be mixed; and with an upper marker 3, located to indicate the surface level of the aggregate quantity of both ingredients; these markers dividing off the interior of the bottle into two measuring spaces X and Y, as indicated by the dimension lines at the right of Fig. 2. The bottle is further provided with a broad bottom 1^a against which the fluid ingredients may impinge in the shaking operation with rapid spreading effect and consequent increased efficiency in mixing; also a neck 4, which may be of any suitable form, so long as it is adapted to provide a reduced handhold for manipulating the bottle in the process of mixing and provides within the bottle, the inwardly deflecting inclined surfaces 1^b to cause the outer portions of the upwardly moving column of liquid, to flow inwardly and occupy an inner position in returning, thus further increasing the mixing effect; also an enlarged dispensing end 5, a stopper 6 and the finger rest 7 on the stopper. The stopper 6 seats in such position, and the length of the bottle is so proportioned, as to provide an additional or free space Z beyond the measuring spaces, which, added to the measuring spaces, provides an agitating chamber in which the ingredients may travel from end to end and develop a thorough emulsionizing of the ingredients. By having the free space Z of restricted proportions, in comparison with the measuring spaces X and Y, more thorough emulsionizing is attained and a much 11^b

smoother dressing produced than if the ingredients were less confined, and this result is also contributed to by having the general proportions of the bottle as shown, namely 5 with confinement laterally in a more or less restricted column, and agitation longitudinally, which results in causing the ingredient with the heavier specific gravity to drive through and more thoroughly subdivide the 10 lighter, and by having the inwardly deflecting surface 1^b at one end of the agitating space and the outwardly spreading surface 1^a at the other end thereof.

While I have described all of the features 15 which I prefer to embody in the device, it is to be understood that the invention is not limited to the use of all these features in combination, as many of the advantages may be realized in a useful measure at least, even 20 when some of the features are omitted, or substituted by others.

I claim:—

A bottle for measuring, confining and emulsifying the oily and aqueous ingredients 25 of French dressing, comprising an elongated body portion having vertical walls adapted to confine the dressing ingredients and hav-

ing thereon measuring aggregates located to indicate, when the bottle stands erect, the surface level of the appropriate quantity of 30 one constituent, and also the surface level of the aggregate quantity of both constituents, and having a free space above said aggregate quantity marker which, added to the elongated body portion, provides a relatively 35 long and narrow agitating chamber, said bottle having a broad bottom constructed to spread outwardly, a discharge opening, a stopper therefor, and a shouldered handhold around said discharge opening; said stopper 40 having a finger bearing within reach of the finger when the bottle is retained by the handhold, whereby the ingredients when being emulsified are deflected by the walls of the broad bottom toward the center of the 45 bottle.

The foregoing specification signed at Corning, New York, this twelfth day of December, 1914.

TOWNSEND DE M. HAWKES.

In presence of—

SAMUEL HAWKES,
CHARLES H. VOORHEES.
